Chas N. Orpen

UNITED STATES PATENT OFFICE.

CHARLES N. ORPEN, OF NEW YORK, N. Y., ASSIGNOR TO HIMSELF AND JOHN GAUDU, OF SAME PLACE.

IMPROVEMENT IN PLACING RESERVOIRS FOR LAMPS.

Specification forming part of Letters Patent No. **36,060**, dated July 29, 1862.

To all whom it may concern:

Be it known that I, CHARLES N. ORPEN, of the city and State of New York, have invented, made, and applied to use a certain new and useful Improvement in Reservoirs for Lamps; and I do hereby declare that the following is a full, clear, and exact description of the said invention, reference being had to the annexed drawing, making part of this specification, wherein I have represented a vertical section of my said improvement.

In cities and towns particularly a large number of the houses are supplied with gas pipes and fixtures which add to the ornamental appearance, but also allow for the introduction of gas from the gas-works. Since the introduction, however, of coal-oil many persons prefer to use the same, as giving a good light at less cost than gas. The gas-fixtures are generally located at the places most convenient, and my invention provides for the application of a lamp directly to the burner, to take the place of a jet of gas.

The nature of my said invention consists in the introduction of a socket, *a*, in the bottom of the reservoir *b*, which reservoir is to contain the coal or other oil and be provided with any desired wick and burner. The aforesaid socket *a* is of a size and shape to fit over the

gas-burner *c* upon any ordinary gas pipe or fixture, and a small sleeve, *d*, of india-rubber or other suitable yielding material, introduced over the burner, causes the sockets to set more tightly upon the burner.

The reservoir *b* and socket *a* may be of glass or any suitable material, and should have a small base around the socket, in order that the reservoir may stand when lifted off the burner.

By this construction I am enabled to apply a lamp directly to the gas-burner to take the place of a jet of gas, or the same can be lifted off and transported from place to place as required.

What I claim, and desire to secure by Letters Patent, is—

1. The socket *a*, applied in the reservoir *b*, to set over the gas-burner *c*, as and for the purposes specified.

2. The elastic sleeve *d* upon the burner *c*, to receive the socket *a*, as set forth.

In witness whereof I have hereunto set my signature this 28th day of April, 1862.

CHAS. N. ORPEN.
